CLAIM

We claim the ornamental design for a display of a multimedia terminal with transitional graphic image, as shown and described.

DESCRIPTION

FIG. 1 is a front view of a first image of a display of a multimedia terminal with transitional graphic image showing our new design:

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the transitional graphic image sequentially transitions between FIGS. 1-10. The process or period in which an image changes into another image forms no part of the claimed design.

The broken lines represent the display of a multimedia terminal and form no part of the claim.
